SHOE BOTTOM

Frederic A. Parkhurst, Suffield, Conn., assignor to
Monsanto Chemical Company, St. Louis, Mo., a
corporation of Delaware

Application March 23, 1939, Serial No. 263,620

10 Claims. (Cl. 36—24.5)

This invention relates to the bottoms of boots and shoes and has for an object to provide a light and inexpensive shoe bottom comprising a shank, outsole and heel all of which parts can be readily molded by well known means and methods from suitable plastic materials and thereafter combined into a unitary structure of attractive appearance and great durability.

More or less satisfactory molded plastic boot and shoe heels have heretofore been produced, but it has been found extremely difficult, if not impossible, to attach them to conventional shoes with the requisite security, since the nails or screws commonly employed for this purpose are unsuited to the attachment of heels of this character. The present invention has for one of its objects the provision of a shoe bottom structure including a molded plastic heel securely attached in such manner that it will be retained in proper position throughout the life of the shoe.

The foregoing and other objects of the invention, together with means whereby the latter may be carried into effect, will best be understood from the following description of certain forms or embodiments thereof shown in the accompanying drawings, these, however, having been chosen for purposes of exemplification merely, it being obvious that the invention, as defined by the claims hereunto appended, may be otherwise embodied without departure from the spirit and scope thereof.

In said drawings:

Fig. 1 is a side elevation and Fig. 2 a bottom plan view, both partly broken away, of a shoe shank element constituting one feature of the present invention.

Figs. 3, 4 and 5 are sections taken substantially on the lines 3—3, 4—4 and 5—5, respectively, of Figs. 1 and 2.

Fig. 6 is a side elevation and Fig. 7 a bottom plan view of a somewhat similar shank member combined with an outsole member.

Fig. 7a is a section taken substantially on the line 7a—7a, Fig. 7.

Fig. 8 is a side elevation, partly in section of a shank member similar to that shown in Figs. 1 and 2 having a heel attached thereto, and embodied in a shoe.

Fig. 9 is a section, partly broken away, taken substantially on the line 9—9, Fig. 8.

Fig. 10 is a side elevation, partly in section, of the unit shown in Figs. 6 and 7, combined with a heel of a somewhat different construction from that shown in Figs. 8 and 9, and embodied in a shoe.

Fig. 11 is a section, partly broken away, taken substantially on the line 11—11, Fig. 10.

Fig. 12 is a longitudinal section showing an integrally united shank and heel.

Fig. 13 is a similar view of a complete unitary shoe bottom including an integrally united heel, shank, and sole, the construction of the heel and shank being slightly different.

Referring to Figs. 1 to 5, there is shown at 15 10 a shoe shank member die cast or molded in accordance with well-known methods from a suitable plastic material or composition, having the requisite strength, durability and hardness, such, for example, as cellulose acetate molding compositions, molding resins, the vinyl acetals and chlorides, styrene, etc. The said shank member is formed with a heel seat portion 16 and has molded and embedded therein a stiffening member 17 preferably comprising a strip of perforated sheet steel. The heel seat portion 16 in the construction shown is adapted to cooperate with and have attached thereto a molded plastic heel of the general character more fully described in a co-pending application filed March 23, 1939, Serial No. 263,619. Said heel, as shown in Figs. 8, 9, and 12, comprises a shell 18 molded in a suitable shape from plastic material similar to that of which the shank 15 is composed, said shell having in its bottom a socket 19 to receive and retain the shank 20 of a toplift 21 likewise molded from a similar composition. At its upper or heel seat end, the shell 18 is formed with interior upright integral reinforcing or stiffening ribs 22, and said shell is further reinforced 20 and stiffened by a vertical transverse web 40, said web further acting to stiffen and reinforce the socket 19, and being preferably joined at at least one end to one of the ribs 22. The heel seat portion 16 of the shank 15 is formed with recesses 25 23 to receive the projections formed by the upper ends of the ribs 22 and is further provided with a projection in the form of a pair of parallel ribs 24 forming between them a recess or groove 20 25 to receive the upper projecting edge of the web 40 which is thereby embraced by the said ribs. The interengaging recesses and projections on the heel and the heel seat portion of the shank 15 interlock with one another to prevent relative lateral movement of the former on the latter, so that by securing the parts together into a unitary structure, as by the use of a suitable cement or by softening the engaging surfaces by a suitable solvent, the heel will be securely fastened to the shank and become a substantially integral part thereof.

In Figs. 10, 11 and 13 is shown a modified form of heel shell 18a in which the ribs 22 and web 40 are omitted, although a short reinforcing web 26 for the walls of the socket 19 which receives the toplift shank 20 is preferably provided. In this form of the invention the heel seat portion 16a of the shank is formed with a rabbeted groove or marginal recess 23a to receive the projecting upper edge 22a of the heel shell 18a which is cemented or welded therein as above described.

It will be observed that in each of the forms above described, and whether or not the ribs 22, web 40, recesses 23, and groove 25 are employed, the molded heel seat portion of the shank includes an integral projecting portion which is received within the open top of the heel shell and is, at least in part, enclosed and engaged by the upper rim of the latter to which it is united to form a strong, rigid, and substantially integral structure.

As shown in Figs. 6, 7, 7a and 13, a shank member 15a similar to that shown in Fig. 10 is combined into a unitary structure with an outsole member 27, likewise molded from a plastic material similar to that of which the shank and heel are formed, and secured thereto in a manner similar to that in which the heel is secured to the shank, namely, by cementing or welding by means of a solvent. As shown in Figs. 6 and 7 the outsole member 27 underlies the forward portion of the shank 15a and abuts at its rear end against a shoulder 28 formed in the forward edge of the heel seat portion 16a of the latter. If desired, a short tap sole member 29 may be provided, as shown in Fig. 8, and suitably secured, as by cementing or welding, to the forward end of the shank member 15.

The construction above described is such that the heel with its reinforcing elements and toplift receiving socket, the shank with its stiffener and heel seat portion shaped complementary to the contiguous portions of the heel, and the sole, may be conveniently molded separately, and thereafter when assembled and cemented or otherwise secured together as above described to form a substantially integral complete shoe bottom which can be applied as a unit to a shoe of any suitable type and whose parts, when in place, are securely bonded together against possible disintegration.

I claim:

1. In a boot or shoe, a shank composed of molded plastic material and having a stiffening member embedded therein and a heel seat portion, and a heel likewise composed of molded plastic material and secured to said heel seat portion, said heel seat portion and heel having a plurality of interengaging recesses and projections united to one another and constituting the principal means of attachment of said heel to said seat portion.

2. In a boot or shoe, a hollow molded plastic heel having an open top, and a molded plastic shank including a heel seat portion having an integral projection received within the open top of said heel, said projection having a recess, and said heel having an integral interior projection received in said recess and said heel engaging and interfitting said heel seat portion at its edges.

3. In a boot or shoe, a hollow molded plastic heel having an open top, and a molded plastic shank including a heel seat portion having a plurality of integral projections received within the open top of said heel, said heel having an integral interior projection interfitting between the projections on said seat portion and said heel engaging and interfitting said heel seat portion at its edges.

10 4. In a boot or shoe, a hollow molded plastic heel having an open top, and a molded plastic shank including a heel seat portion including an integral projection received within the open top of said heel and enclosed and engaged by the latter, said heel having interior reinforcing projections, and said heel seat portion having recesses within which said projections are received.

20 5. In a boot or shoe, a shank composed of molded plastic material and having a heel seat portion, and a heel comprising a hollow shell of molded plastic material and having interior reinforcing ribs, said heel seat portion having recesses to receive the ends of said ribs.

25 6. In a boot or shoe, a shank composed of molded plastic material and having a heel seat portion, and a heel comprising a hollow shell of molded plastic material and having a transverse reinforcing web, said heel seat portion having a groove in which the adjacent edge of said web is received.

30 7. In a boot or shoe, a shank composed of molded plastic material and having a heel seat portion, and a heel comprising a hollow shell of molded plastic material and having interior reinforcing ribs and a transverse reinforcing web, said heel seat portion having recesses to receive the ends of said ribs and a groove in which the adjacent edge of said web is received.

35 8. In a boot or shoe, a shank composed of molded plastic material and having a heel seat portion, and a heel comprising a hollow shell of molded plastic material and having interior reinforcing ribs and a transverse reinforcing web, joined at at least one end to one of said ribs, said heel seat portion having recesses to receive the ends of said ribs and a groove in which the adjacent edge of said web is received.

40 9. In a boot or shoe, a shank composed of molded plastic material and having a heel seat portion, and a heel comprising a hollow shell of molded plastic material and having a transverse reinforcing web, said heel seat portion having a pair of parallel ribs embracing between them the adjacent edge of said web.

45 10. A boot or shoe having a bottom comprising a shank composed of molded plastic material and having a stiffening member embedded therein and a heel seat portion, an outsole also composed of molded plastic material, and a heel likewise composed of molded plastic material, said heel seat portion and heel having integral interengaging recesses and projections united to one another and constituting means for attaching said heel to said seat portion, and said outsole and heel being secured to said shank and forming therewith a unitary structure.

FREDERIC A. PARKHURST.
